UNITED STATES PATENT OFFICE

AXEL HOLMSTRÖM, OF VIGGBYHOLM, SWEDEN

AIR-COOLING SYSTEM

Application filed October 17, 1923, Serial No. 669,134, and in Germany June 16, 1923.

My invention is a cooling device based upon evaporation of moisture within porous material and is applicable to a variety of uses.

5 The purpose of my invention is to utilize an impeller having blades of porous material for the distribution of the moisture and to feed moisture to the blades through the material itself.

10 A further purpose is to have the blades part of a container wholly made up of porous material, charging the container with the liquid to be evaporated and utilizing centrifugal force and the porosity of the material to 15 distribute the liquid to the surface of the blades.

A further purpose is to provide a cooling box or refrigerator with circulation by means of a moisture-distributing impeller giving 20 circulation downwardly along the outer parts of the box and return circulation through the middle portion of the box.

A further purpose is to provide for the 25 direct distribution and coincident moistening of air by the use of impellers angularly placed and of porous material saturated or nearly saturated with moisture.

Further purposes will appear in the specification and in the claims.

30 I prefer to illustrate my invention by a few forms only, selecting forms which are practical, efficient, economical and inexpensive and which at the same time well illustrate the principles of my invention.

35 Figure 1 is a vertical longitudinal section of a cooling receptacle of the refrigerator type embodying my invention.

Figure 2 is a section of Figure 1 upon line 2-2 of Figure 1, the impeller being shown 40 in side elevation.

Figure 3 is a fragmentary section of a structure corresponding to Figure 1, but showing a deeper impeller reservoir.

45 Figure 4 is a section of Figure 3 taken upon line 4-4.

Figure 5 is a section of an impeller corresponding generally to Figures 1 and 3 but showing a different kind of impeller blade.

50 Figure 6 is a section of Figure 5 taken upon line 6-6.

Figure 7 is a longitudinal section corresponding generally to Figure 1 but showing a slightly different form.

In the drawings similar numerals indicate like parts.

Describing in illustration and not in limitation and referring to the drawings.

My invention is based upon the principle that moisture will permeate the walls of an article of porous material, with the result 60 that porous material may be used to distribute in vapor form liquid received by the material in drops or in bulk. Though this capability differs somewhat with the characteristics of the liquid used it is true to a 65 greater or lesser extent of all freely flowing liquids.

Taking up first the forms of Figures 1 and 2, the casing 15, which may be a refrigerator casing, is provided with a door 16, and 70 inner walls 17, 18 of a cooling chamber (parallel to two opposite outer walls of the casing) partitioning off the chamber from side passages 19, 20. The walls 17 and 18 connect with top and bottom upward flanges 75 21 and 22 about openings 23 and 24.

The walls 17 and 18 carry brackets 25, 25', by which shelves 26 are supported, the shelves being of perforated or screen material. These shelves may support articles 80 to be cooled.

The upper part of the casing is open at 27 above the opening 23 and is provided with a flanged bracket 28 supporting a bearing 29. The bearing is capped by thrust bearing 30 85 for pulley wheel 31 by which shaft 32 is driven by motor 33 and belt 34.

The shaft 32 carries an impeller 35 comprising chiefly impeller blades 36 and a body 37 which is hollow to provide a chamber or 90 receptacle 38.

For convenience of access the top and bottom of the body are formed separately and are shown at 39 and 40, sealed by gaskets 41 to protect against leakage. Any convenient means of fastening may be used. The cover 39 is provided with an inlet filling opening 42 which is closed by plug 43.

The means shown for holding the parts together comprise a head 44 upon the lower end 100

of the shaft, a nut 45 threaded upon the upper part of the shaft above the cover and any desired washers 46 between. A drip pan 47 is shown at the bottom.

6 The container and integral impeller blades are made of porous earthenware or similar material which will soak up the liquid from the chamber 38 and distribute it to the impeller blades. From these, as the impeller is rotated, the moisture will evaporate until the surrounding air has become saturated.

10 The impeller draws the air into the space close to the chamber from above and also from below. That drawn upwardly comes 15 from the cooling chamber through the opening 23 and produces a corresponding flow down the passages 19 and 20.

15 By this means the air within the whole casing becomes saturated with water vapor 20 and correspondingly cooler.

25 In this form the casing is substantially closed below the opening 27. Air saturated with vapor escapes at the outer part of the top opening and an equal quantity of fresh (dry) air enters at the inner portion of the top, largely drawn in by the action of the impeller. The vigorous action of the impeller greatly increases the rapidity of this diffusion which should be merely great 30 enough to maintain the temperature within near the dew-point temperature.

35 The natural liquid for use is of course pure water, and that is sufficient and satisfactory for the purpose intended in this form. However obviously in other forms where 40 house distribution of the cool air is contemplated, any designed proportion or quantity of perfume, however small, or of disinfectant however large, may be distributed along with the moistened and cooled air.

45 The impeller is charged with water at the plug 43.

50 In the form shown in Figure 3, the hollow body 37' is given additional height so as to give room for a deeper chamber 38 to gain the dual benefits of an additional quantity of liquid for vaporization and a slight additional height of pressure to assist the capillary permeation of the liquid through the body material and into the vanes or blades 55 36 so as to increase the speed of distribution. The structure is otherwise the same.

55 In the form shown in Figure 5 the same size body and chamber are shown but the shaft 32' is made hollow in order that it may be used as a conduit for the flow of water into this chamber 38 from any desired height of liquid. Openings 48 permit flow from the hollow shaft into the chamber and the bottom of the tube is closed by a plug 49 upon the head 44'. The tube is sealed on the outside against the head.

60 Of course the type of fan and the number of vanes used can be varied greatly. In 65 Figure 4 straight vanes are shown such as

are seen in Figures 1, 2 and 3. In Figure 6 the vanes 36' are curved. They may be angular as in Figure 9 and may then be plane or helical.

65 In Figure 7 the entire inner (storage) compartment is of tubular section, formed between the walls 17', 18' and central tubular walls 50 and the top and bottom are closed, so that the upward flow of the air is confined to the tubular space 51. A different 75 form of bracket is shown at 28'.

80 In the forms in Figures 1-7 the impeller is rotated giving out vapor to the air and causing outward and downward movement of air which comes up through the compartment to be cooled. Part of the air as it comes up is dispersed into the outer atmosphere and its place is taken by dry air coming in from the top and moistened by the impeller.

85 Obviously in view of my invention other forms and variations of my invention will occur to those skilled in the art which will obtain all or a part of the benefit of my invention without copying the forms shown; and it is my intention therefore to cover 90 herein all of such modifications and changes of the principles of my invention as come within reasonable spirit and scope of the invention.

95 Having thus described my invention, what I claim as new and desire to secure by Letters Patent is:—

100 1. A cylindrical impeller body of material permeable to water having a water inlet, an enlarged interior reservoir and having its upper end initially open, means for closing the bottom of the impeller and a mount for the impeller adapted to rotate it about the axis thereof and having blades of the same permeable material as the impeller and integral therewith. 105

110 2. A shaft, a sealed, vertically disposed hollow impeller thereon having blades disposed substantially parallel with the shaft thereof and made of material permeable to moisture in combination with means for supplying liquid to the hollow of the impeller, a casing about and below the impeller, a receptacle within the casing spaced from the sides of the casing and open at the top and bottom and shelves within the receptacle permitting passage of air upwardly through the receptacle. 115

120 3. A shaft, a hollow impeller thereon of material permeable to moisture disposed substantially parallel with the shaft thereof in combination with a casing about the impeller and a storage compartment within the casing spaced therefrom to allow air to pass down about the sides of the compartment, 125 having an inlet opening at the bottom and an outlet opening at the top and permitting flow of air upwardly through the compartment.

130 4. A shaft, a hollow impeller thereon of material permeable to moisture and disposed

substantially parallel with the shaft thereof in combination with a casing about the impeller and a storage compartment within the casing spaced therefrom to allow air to pass about the sides of the compartment between the impeller and the casing.
